CLAIM

The ornamental design for a dispenser as shown and described.

DESCRIPTION

FIG. 1 is a top perspective view of a dispenser showing the claimed design;

FIG. 2 is a bottom perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof; and,

FIG. 8 is a bottom view thereof.

The dashed broken lines in the figures show portions of the dispenser that form no part of the claimed design.

1 Claim, 8 Drawing Sheets

Related U.S. Application Data

a continuation of application No. 29/808,289, filed on Sep. 17, 2021, now Pat. No. Des. 996,114.
